US0D1043065S

(12) **United States Design Patent** (10) **Patent No.:** **US D1,043,065 S**
(45) **Date of Patent:** ** *Sep. 24, 2024

(54) **FOOTWEAR SOLE**

(71) Applicants: **D'Wayne Edwards**, Beaverton, OR (US); **Wichaya Chantarasamee**, Aloha, OR (US)

(72) Inventors: **D'Wayne Edwards**, Beaverton, OR (US); **Wichaya Chantarasamee**, Aloha, OR (US)

(*) Notice: This patent is subject to a terminal disclaimer.

(**) Term: **15 Years**

(21) Appl. No.: **29/760,973**

(22) Filed: **Dec. 4, 2020**

Related U.S. Application Data

(63) Continuation of application No. 29/668,928, filed on Nov. 2, 2018, now Pat. No. Des. 905,396, which is a continuation of application No. 15/217,748, filed on Jul. 22, 2016, now Pat. No. 10,130,137.
